[57] CLAIM

The ornamental design for a combination toothbrush and floss holder, as shown and described.

DESCRIPTION

FIG. 1 is a side elevational view of a combination toothbrush and floss holder, showing my new design, the opposite side being a mirror image thereof;

FIG. 2 is a top plan view thereof.

FIG. 3 is a bottom plan view thereof.

FIG. 4 is a left end elevation view thereof.

FIG. 5 is a right end elevation view thereof.
